UNITED STATES PATENT OFFICE

PAUL O. UNGER, OF CHICAGO, ILLINOIS, ASSIGNOR TO WILSON-JONES COMPANY, OF CHICAGO, ILLINOIS, A CORPORATION OF MASSACHUSETTS

LOCKING MECHANISM FOR BINDER POSTS

Application filed February 25, 1932. Serial No. 595,121.

This invention relates to locking mechanism for binder posts, and it is an object of this invention to provide means whereby the locking posts for loose leaf binders may be readily actuated for locking the two binder heads in adjusted position.

The invention comprises the novel structure and combination of parts hereinafter described and more particularly pointed out and defined in the appended claims.

In the accompanying drawings which illustrate certain preferred embodiments of this invention and in which similar reference numerals refer to similar features in the different views:

Figure 1 is a fragmentary end elevational view of a loose leaf binder involving this invention.

Figure 2 is an enlarged sectional view taken upon the line II-II of Figure 1 looking in the direction of the arrows and illustrating the interior parts in elevation.

Figure 3 is an enlarged sectional view taken upon the line III-III of Figure 1 looking in the direction of the arrow and with the loose sheets omitted.

Figure 4 is an enlarged fragmentary sectional view taken upon the line IV-IV of Figure 2 looking in the direction of the arrows.

Figure 5 is an enlarged fragmentary sectional view taken upon the line V-V of Figure 4 looking in the direction of the arrows.

Figure 6 is an enlarged vertical sectional view taken through a modified form of locking post.

Figure 7 is an enlarged sectional view taken upon the line VII-VII of Figure 6 looking in the direction of the arrows.

Figure 8 is a further modified form of locking post representing a vertical section upon an enlarged scale.

Figure 9 is an enlarged sectional view taken upon the line IX-IX of Figure 8 looking in the direction of the arrows.

Figure 10 is an enlarged sectional view taken upon the line X-X of Figure 8 looking in the direction of the arrows.

Figure 11 is an enlarged vertical sectional

view of another modified form of locking post.

Figure 12 is a bottom plan view of the structure shown in Figure 11.

Figure 13 is an enlarged sectional view taken upon the line XIII-XIII of Figure 11.

Describing the invention in the form shown in Figures 1 to 5, it will be noted that only those parts of the binder that cooperate with the invention have been illustrated. To this end there is shown a compression member or binder head 1 having a flange 2 that extends over the back of the binder. Cooperating with the binder head 1, there is a second binder head 3 having marginal upturned flanges over which a cover plate 4 extends. This cover plate 4 has a right-angle flange 5 that extends over the back portion of the binder. The compression member 3 and cover 4 form a casing for a purpose that will later appear.

Suitable impaling posts 6 are secured to the compression members 1 and 2 as shown in Figure 3 for confining loose sheets thereon. Intermediate the impaling posts 6 there is a locking post which consists of a tubular member 7 which is secured in the binder head 1. This tubular member 7 has a flat portion 8 upon one portion of its periphery as shown in Figure 5 and a portion of this flat part 8 is provided with serrations or teeth 9. Within the tubular member 7 there is a locking post 10 which is provided with a flattened portion 11 as shown in Figure 5, and this flattened portion is provided with teeth or serrations 12 as shown in Figure 4 for engaging the notches between the teeth 9 on the tubular member 7 when the post 10 is rotated. Adjacent the teeth 12 on the post 10 there is an arcuate cut-out portion 13 as shown in Figure 5 which is adapted to be positioned opposite the teeth 9 when the post 10 is in unlocked position.

The locking post 10 extends into the aforementioned casing and a gear segment 14 is secured upon the upper end of said post 10 within the casing. This gear segment is provided with a number of teeth 15 which are adapted to be engaged by suitable teeth 16

on a rack bar 17 which is slidably mounted in the casing and maintained in engagement with said segment by one wall of the casing as shown in Figs. 2 and 4. This rack bar 17 extends beyond one end of the casing where it is provided with an inturned flange 18 which forms a finger piece for sliding the rack bar inwardly and outwardly. With reference to Figure 2, it will be noted that 10 a pair of stop members 19 are secured in the aforementioned casing, one upon each side of the gear segment 14 and that the rack bar 17 is cut away to provide shoulders 20 and 21 which are adapted for engaging the stops 19 15 for limiting the longitudinal movement of such rack bar 17.

By sliding the rack bar 17 inwardly and outwardly, the locking post 10 is rotated for engaging the teeth 12 with the teeth 9 on the 20 tubular member 7 for disengaging the same therefrom. It will of course be understood that the binder illustrated is of the expandable type in which the compression members may be separated or brought closer together in 25 accordance with the number of sheets in the binder and that the locking post is for the purpose of locking such binder in its adjusted position. When it is desired to open or expand the binder, the slide 17 will be 30 pulled outwardly for rotating the locking post 10 for disengaging the teeth thereof from the teeth on the tubular member 7 whereby the compression members may be separated.

35 When it is desired to close the binder after the same has been opened for the insertion of additional sheets or for the removal of sheets, the compression members are forced together and the slide 17 is pushed inwardly to rotate 40 the locking post 10 to bring the teeth thereof into locking engagement with the serrations on the tubular member 7.

Instead of using the positive locking feature shown in Figures 1 to 5 comprising 45 the interengaging teeth or serrations, frictional locking means may be used as shown in Figures 6 to 10. In referring first to Figures 6 and 7, there is illustrated a construction in which a tubular member 22 is 50 secured to the compression head 1 and within this tubular member 22 there is a sleeve post 23 into which a plunger rod 24 or locking post is threaded. The plunger rod 24 extends into the casing and carries the gear segment 55 14 whereby the same may be rotated as in the first form of the invention illustrated. The sleeve 23 is provided with a pocket or socket at its lower end which is closed by a bottom plate 23^a, and within this socket there are a 60 pair of friction elements 25 which are in the form of ordinary bearing balls. Between the balls 25 there is a third ball 26 which is partly located in the bore that contains the plunger 24. The plunger 24 is adapted to 65 be rotated by the slide 17 and the gear seg-

ment 14, and when this plunger rod is rotated inwardly, it will engage the ball 26 and tend to separate the balls 25 and force the same into frictional engagement with the tubular member 22 for locking the parts together 70 against movement.

In the form of the invention shown in Figures 8 and 10, the tubular member 22 contains an eccentric sleeve 27 which is secured at one end to the compression head 3. Within the eccentric sleeve 27 there is a post 28 which carries the gear segment 14 in the casing. This post 28 has an enlarged eccentric head 29 below the eccentric sleeve 27, and this head is provided with a socket 30 adjacent 80 its periphery for carrying a bearing ball 31 which is adapted to be rotated into frictional engagement with the sleeve or tubular member 22. By the eccentricity of the parts, the post 28 may be rotated by the aforementioned 85 slide 17 to cause a binding relation between the head 29 of such post and the tubular member 22 through the instrumentality of the bearing ball or friction element 31. When the friction element 31 is rotated to relieve 90 the binding relation, the binder may be readily expanded.

In Figures 11 to 13 there is illustrated a modified form of mechanism for positively locking the different members of the locking 95 post. In this form of the invention the tubular locking member 32 is provided with internal threads 33. An eccentric sleeve 34 is secured to the clamping head 3 and a locking post 35 is rotatably mounted in the 100 eccentric sleeve 34. This post 35 extends into the aforementioned casing and carries the gear segment 14 at its upper end for actuation by the aforementioned slide 17. The locking post 35 extends below the eccentric 105 sleeve 34 and its lower end is in the form of an eccentric threaded head 36 which is adapted to be rotated into and out of engagement with the threads on the tubular member 32. This rotation can of course be effected by the 110 aforementioned slide. Through the eccentricity of the parts, the head 36 can be quickly rotated into locking engagement with the threads and can be just as quickly rotated out of locking engagement with the threads 115 of the tubular member 32.

It will be evident that the different forms of locking posts require only a short movement of the slide 17 for rotating the same into or out of locking engagement, so that a 120 great deal of time and labor may be saved in the use of the binder. It will be further appreciated that the reciprocation of the slide is limited so that no damage can be done to the parts that might occur if the locking post could be rotated an unlimited extent to cause such binding or interlocking engagement that might rupture parts of the locking mechanism. It will also be evident 125 that the stops 19 govern the rotation of the 130

locking post in that the rotation thereof is prevented after a predetermined rotation in either direction. In other words, the rotation of said post will be stopped when it is in locking position and also when it is in unlocking position.

I am aware that many changes may be made and numerous details of construction may be varied through a wide range without departing from the principles of this invention and I, therefore, do not purpose limiting the patent granted hereon otherwise than necessitated by the appended claims.

I claim as my invention:

15 1. In a loose leaf binder, a clamping head, a tubular member thereon, a casing, a rotatable post on said casing and extending into said tubular member, and means for engaging said post and tubular member through 20 a predetermined rotational movement, comprising a gear upon said post and located within said casing, a slideable rack bar within said casing and maintained in engagement with said gear by a wall of said casing, said 25 rack bar extending beyond said casing and being provided with a handle, said rack bar also having spaced shoulders within said casing and a pair of stops in said casing between said shoulders for limiting the movements 30 of said rack bar and the rotational movements of said post to locking and unlocking positions.

2. In a loose leaf binder, a clamping head having a tubular member thereon, a casing, a rotational locking post on said casing extending into said member, and means for engaging said post and tubular member by a 70 predetermined rotational movement in one direction and disengaging the same therefrom by a predetermined rotational movement in a reverse direction, comprising a gear upon said post within said casing, a slideable 75 rack bar within said casing and maintained in engagement with said gear by a wall of said casing, and means for limiting the sliding movements of said rack to locking and unlocking positions of said post.

3. In a loose leaf binder, a clamping head having a hollow post thereon, a casing, a rotational locking post on said casing extending into said hollow post, and means for engaging and disengaging said locking post 80 and hollow post by a predetermined rotational movement, comprising a gear segment upon said locking post located within said casing, a slideable rack bar within said casing and engaging said gear segment, said rack 85 bar having a pair of spaced shoulders, and a pair of stops in said casing between said shoulders for limiting the sliding movements of said rack bar to limit the rotation of said locking post to engaged and disengaged positions.
